(57) **CLAIM**

The ornamental design for a circular insect trap, as shown and described.

DESCRIPTION

FIG. 1 illustrates a perspective view of a circular insect trap comprising a new design.

FIG. 2 is front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is an exploded perspective view thereof; and, FIG. 9 is a perspective bottom view of a top cap portion thereof.

The broken lines are for environmental purposes only and form no part of the claimed design.
